TRAY

William R. Vermillion, Kansas City, Mo.
Application January 13, 1954, Serial No. 28,509

Term of patent 7 years

(Cl. D44—10)

Fig. 1.

Fig. 2.

Fig. 3.

To all whom it may concern:

Be it known that I, William R. Vermillion, a citizen of the United States, residing at Kansas City, in the county of Jackson and State of Missouri, have invented a new, original, and ornamental Design for a Tray, of which the following is a specification, reference being had to the accompanying drawing forming a part thereof.

Fig. 1 is a perspective view of a tray, showing my new design.

Fig. 2 is an end elevational view thereof; and

Fig. 3 is a bottom plan view thereof.

I claim:

The ornamental design for a tray, as shown.
